UNITED STATES PATENT OFFICE

WILLIAM GILLIS, OF FORT WORTH, TEXAS

SAFETY ELEVATED BANK AND VAULT PROTECTOR

Application filed June 5, 1929. Serial No. 368,703.

This invention relates to a device for bank protection against robbery and more particularly to an elevated structure with a stairway which can be raised out of reach and thereby shut off the access to the bank vault.

In brief the device consists of an elevated cage to accommodate several clerks. This cage is placed adjacent the door of the bank vault so that entrance to the vault door can only be had through the elevated cage. Pivotally attached to the cage is a stairway which can be raised when any danger due to a hold-up arises so that the exit to the bank vault will be shut off. The walls of the cage are preferably made of armored steel and provided with openings so the crew within the cage can fire upon the hold-up men when any such emergency arises.

Placed within the cage is a winch to which is attached the end of the cable for raising or lowering the stairway. A system of signaling is provided operable from the main floor to indicate to the crew of the cage when to raise or lower the stairway and when to be cautious.

Other objects of the invention will appear as the disclosure progresses. The drawings are intended merely to indicate a possible embodiment of the invention. It is therefore not intended to limit the invention to the embodiment illustrated but rather to define such limits in the appended claims. For a more general understanding of the invention attention is now called to the drawings. In these drawings like reference characters denote like parts throughout the specification.

In the drawings:

Figure 1 is a side elevation of the device.

Figure 2 is a front elevation.

Figure 3 is a top view thereof.

Figure 4 is a detail view of the winch with the cable removed and

Figure 5 is a wiring diagram.

Referring now to the drawings in detail numeral 1 designates the cage large enough to accommodate several clerks supported on the pedestal 2 high enough to be out of the reach of any person.

Pivoted to the brackets 3 at the bottom of the cage is a stairway 4. At the bottom of

the stairway is attached one end of a cable 5 which leads to a manually operated winch 6 placed within the cage.

The cage 1 is preferably placed against the wall 7 of the bank vault entrance door. Cut in the floor 9 and side 10 of the cage are lookout slots 11 through which the men in the cage can fire their pistols or guns. In addition to these slots lookout doors 12 placed waist high are provided in the walls of the cage.

The winch 6 comprises a drum 13 keyed to the shaft 14 and is supported in the bearings 15 which are fastened to the wall of the cage. At the end of the shaft 14 is a crank handle 16 for manually operating the winch. Attached to the drum 13 is the end of the cable 5. Cut in the flange 17 of the winch drum is a ratchet 18 which engages with the pawl 19. The pawl is pivoted on the shaft 20 which is partly threaded as at 21 and is supported by the internally threaded bearing 22 attached to the wall of the cage. Keyed to the shaft 20 on both sides of the pawl 19 are collars 23. At the opposite end of the shaft is a handle 24. The operation of the winch is as follows: When it is desired to raise the stair the handle 16 of the winch is revolved anti-clockwise. This will cause the cable 5 to wind up on the drum 6 and lift the stair on the pivoting support 3. The pawl 19 will successively come in contact with the teeth of the ratchet and prevent the back winding of the cable. When it is desired to lower the stair it will not be necessary to give same a preliminary lift so as to disengage the pawl from the ratchet as is the practice in the usual form of winches but all that would be required would be to revolve the handle 24 and the pawl will move to the left out of engagement with the ratchet as indicated in Figure 4. The stairway could then be lowered.

As shown in Figure 1 the cable 5 passes over a roller 25 on the exterior of the cage. This arrangement is for the purpose of obtaining a better leverage as the center of the roller is beyond the center of the stair pivoting points and thereby operate the stair in an easier manner. In addition means are pro-

vided to balance the stair on its pivoting points so as to operate the stair without much energy. This means consists of a balance weight 26 supported by the arm 27 which is attached to the stairway 4. The arm is long enough in order to bring the weight to the left of the stair pivots as shown in Figure 1 and counterbalance the weight of the stairway itself.

At the head of the stairway is a door 28 which provides egress and ingress to and from the cage. The walls of the cage are preferably made of armour plate and held together by the angle irons 29 at the corners.

15 Signaling means are provided to indicate to the crew of the cage operable from the main floor when to be cautious, and when to raise or lower the stairway. The said means consists of a series of three electric lights or bulbs 30, 31 and 32 placed within the cage as shown in Figure 3. Leading from the electric bulbs are suitable conductors 33, 34 and 35 which connect to electric switches 36, 37 and 38 placed conveniently on the main floor of the bank. The electric bulb are colored white, red and yellow respectively. When the switch 36 is closed the red colored bulb 32 will light up and indicate danger so that the stairway should be lifted immediately. When the switch 37 is closed the white colored bulb 31 will light up and indicate that the stairway should be lowered. When the switch 38 is closed the yellow colored bulb 30 will light up and indicate caution. Numeral 39 indicates the battery.

25 It will thus be seen that I have provided a simple and efficient means to protect the funds of a bank from theft. In the event of a hold-up the stairway can be raised when the signal indicates such action and thus shut off the access to the vault. Also the portholes can be used to aim on the hold-up men when such action becomes necessary. The winch is in the interior of the cage so the stair can be operated in perfect safety. The stair is counterbalanced for ease of operation.

30 Having described my invention, I claim:

1. In a device of the class described in combination, an elevated cage supported on a pedestal, a stairway leading to said cage, said stairway pivoted where it joins the cage, an elongated arm fastened to said stairway, a counterbalance weight attached to said elongated arm, the vertical axis of said weight extending beyond the pivoting point of said stairway, a winch within the cage having a cable attached thereto, the opposite end of said cable attached to the lower end of the said stairway, said winch including a pawl and ratchet and means to disengage the pawl from the ratchet by moving said pawl sideways out of engagement with said ratchet.

2. In a device of the class described in combination, an elevated cage supported on a pedestal, a stairway leading to said cage,

said stairway pivoted where it joins the cage, a winch including a pawl and ratchet within the cage having a cable attached thereto, the opposite end of the cable attached to the lower end of the said stairway, a roller attached to the outside of said cage over which the cable passes, the center of said roller extending to the right of the pivoting point of the stairway, and means to disengage the pawl from the ratchet by moving said pawl sideways, said means including a horizontally movable shaft to which is attached at one end the said pawl.

35 In testimony whereof I affix my signature.

WILLIAM GILLIS.
